(57) **CLAIM**

The ornamental design for a surge protector as shown and described.

DESCRIPTION

FIG. 1 is a front, left and top perspective view of a surge protector showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a perspective view of another state of the surge protector thereof.

The broken lines are included for the purposes of illustrating portions of the surge protector that form no part of the claimed design.

1 Claim, 9 Drawing Sheets
